BLADE SUPPORTING SPIDER FOR LAWN MOWERS

Clayton K. Cole, Kalamazoo, Mich., assignor to Atlas
Press Company, Kalamazoo, Mich., a corporation of
Michigan

Application June 7, 1952, Serial No. 20,082

Term of patent 14 years

(Cl. D40—1)

Fig. 1.

Fig. 2.

Fig. 3.

To all whom it may concern:

Be it known that I, Clayton K. Cole, a citizen of the United States, residing at Kalamazoo, county of Kalamazoo, State of Michigan, have invented a new, original, and ornamental Design for a Blade Supporting Spider for Lawn Mowers, of which the following is a specification, reference being had to the accompanying drawing, forming a part hereof.

Fig. 1 is a side elevational view of a blade supporting spider for lawn mowers embodying my new design.

Fig. 2 is a top plan view of the spider shown in Fig. 1.

Fig. 3 is a side elevational view of the spider shown in Fig. 1 taken from the opposite side.

I claim:

The ornamental design for a blade supporting spider for lawn mowers, as shown.
